(57) **CLAIM**

I claim the ornamental design for the door plate sanitizer, as shown and described.

DESCRIPTION

FIG. 1 is a front, right, and top perspective view of a door plate sanitizer in accordance with the present invention, wherein the door plate sanitizer is shown attached to a door and at least partially surrounding a door plate of the door; FIG. 2 is a front, right, and top perspective view of the door plate sanitizer;

FIG. 3 is a front elevational view of the door plate sanitizer; FIG. 4 is a rear elevational view of the door plate sanitizer; FIG. 5 is a right side elevational view of the door plate sanitizer;

FIG. 6 is a left side elevational view of the door plate sanitizer;

FIG. 7 is a top plan view of the door plate sanitizer; and, FIG. 8 is a bottom plan view of the door plate sanitizer. The dashed dot lines are for the purpose of illustrating environmental structure and form no part of the claimed design.

The dash dash lines represent portions of a door plate sanitizer and form no part of the claimed design.
